UNITED STATES PATENT OFFICE.

LEWIS L. HEPBURN, OF NEW HAVEN, CONNECTICUT, ASSIGNOR TO THE MARLIN FIREARMS COMPANY, OF NEW HAVEN, CONNECTICUT, A CORPORATION OF CONNECTICUT.

FIREARM.

No. 927,464.

Specification of Letters Patent.

Patented July 6, 1909.

Application filed June 6, 1908. Serial No. 437,063.

To all whom it may concern:

Be it known that I, LEWIS L. HEPBURN, a citizen of the United States, residing at New Haven, New Haven county, State of Connecticut, have invented certain new and useful Improvements in Firearms, of which the following is a full, clear, and exact description.

My invention relates to improvements in firearms, the object of the invention being to provide certain new and improved features of construction more particularly directed to the so-called closing spring and cartridge handling mechanism within the breech frame, the aim being to secure safety in operation, simplicity in construction and economy in manufacture. These advantages will be well understood by a mechanic familiar with this art, by a reading of the following specification and an examination of the accompanying drawings, in which—

Figure 1 shows a side elevation of a fire-arm, constructed to embody my invention, said illustration being partly in section and partly broken away to reveal the internal construction. Only a portion of the barrel and stock are shown; Fig. 2 shows, in the main, a similar view, certain parts, however, being in a different position; Fig. 3 shows a front elevation of the breech-block, detached; Fig. 4 shows a view of the reverse side of the breech-block from that shown in Fig. 1; Fig. 5 shows a rear elevation of the breech-block; Fig. 6 shows a rear and side elevation of the combined hammer and firing pin, detached; Fig. 7 shows a side elevation of the hammer sear, detached; Fig. 8 shows a side and front elevation of the trigger, detached; Fig. 9 shows a side and edge elevation of a link arranged to connect the trigger with the sear, said part being detached; Fig. 10 is a plan view of the connecting link between the closing spring and breech-block, detached. Fig. 11 illustrates another detail of construction. Fig. 12 is a view similar to Figs. 1 and 2, certain parts being in a different position and other parts being omitted and broken away.

1 is the breech frame. In this particular instance, there is a removable side plate (not shown) adapted to said breech frame, for example, such as set forth in my former patent No. 434,062, dated August 12, 1890, the said side plate being easily removable for the purpose of exposing and permitting

access to the interior of the breech mechanism.

2 is a barrel.

3 is the front reinforce.

4 is a magazine of the "box" or "clip" type, arranged to be detachably connected with the breech frame to the rear of the reinforce 3, and in any suitable manner.

5 represents a portion of the stock.

6 represents the tang, so-called, projecting rearwardly from the reinforce of the breech frame and performing the double function of furnishing a means to hold the stock 5 in place, and of furnishing a housing or carrier for the closing spring.

7 is a plunger reciprocable in the tang 6 and pressed forward by means of a closing spring 8.

9 is the main body of the breech-block arranged to reciprocate in the frame 1, the normal position of the block being advanced to close said breech and the chamber in the barrel.

10 is a link between the breech-block 9 and the forward end of the plunger 7, through which link the power of the closing spring 8 is transmitted to said breech-block. This link 10 preferably has a laterally projecting bearing pin 10^a (see Fig. 10) which takes into a corresponding bearing recess in the breech-block 9. As will be seen, the power of spring 8 is transmitted in almost a straight line to the breech-block and is taken by the latter well forward of the rear end, the forward end of said link 10 being suitably fulcrumed to the block at approximately the middle portion of the breech-block, in the particular form shown. By this means there is very little deflection of the breech-block by reason of the pressure of the plunger 7, thus guaranteeing a free and easy sliding movement of the breech-block in the frame.

The hammer construction, in this instance, comprises a combined hammer and firing-pin, in which the main body 12 serves as a weight, the inertia or momentum of which, when propelled forward, serves to cause the firing-pin end 13 to strike the cartridge in the chamber of the barrel with the desired force, to explode the same.

12^a is a projection or spline, the function of which is to prevent rotation of the hammer body 12 within the breech-block, the side wall of the bore in the breech-block being provided with a groove 9^b, in which said

projection or spline 12^a may slide as the hammer moves to and fro. Obviously, this arrangement might be reversed, the spline or projection being on the breech-block and the 5 groove in the body 12. Such a modification is too apparent to require illustration.

At the under side of the body 12 is a notch 12^b, the function of which will be later explained. The body 12 has a bore entering its 10 rear end to receive a firing-pin actuating spring 14, the thrust of the rear end of said spring being taken on a shoulder within the breech frame, as best seen in Fig. 1. If desired, a guide pin 14^a may be employed to 15 steady the spring 14 when the breech-block 9 and hammer are advanced, as shown in Fig. 1.

15 is a sear pivoted at 15^a and having a nose 15^b arranged to latch into the notch 12^b 20 in the hammer 12 at the proper time, the forward side of said nose 15^b being inclined so that, as the hammer is being cocked, the forward end of the sear will be momentarily pressed down. The sear 15 has, by preference, an angular shoulder 15^c near its fulcrum, arranged to the rear of spring 14, so 25 that said spring will act not only as a means to propel the hammer forward, but will also operate said sear in a direction to cause it to 30 latch into the hammer, thus dispensing with the necessity of a separate spring for that purpose.

15^d is a rearwardly projecting shoulder arranged to be engaged by a laterally projecting shoulder 16^a on the link 16, the opposite 35 end of said link being pivoted, as at 16^b (Fig. 9), to the trigger 17, said trigger being pivoted at 17^a to the breech frame.

30 is a bifurcated spring having the spring 40 ends 31—32. The spring end 31 engages the trigger 17, tending to restore it to its normal position. The spring end 32 engages the link 16 and operates to hold it in such a position as to engage the sear 15.

45 Loaded cartridges are carried in the magazine 4 and are separately released therefrom by the reciprocating action of the breech-block 9, in the well-known manner, unnecessary to describe herein. The breech-block 50 9 is, of course, provided with the usual extractor 18, while the usual ejector 19 may be carried by the breech frame in such position that when a discharged shell is withdrawn by the extractor 18, it will be engaged by 55 said ejector 19 and thrown out of the breech frame through a suitable opening. In this instance, the opening is at the side, as indicated in Fig. 2.

60 9^a is a handle projecting from the breech-block, which furnishes a means to retract the breech-block manually, if any occasion arises therefor. At the rear of the breech-block there is a groove 9^c which affords clearance 65 for the link 16. The forward wall of this groove is indicated in dotted lines (Fig. 4)

and it is so positioned that when the breech-block has reached nearly the limit of its rearward excursion, said wall will strike against the link 16 and tilt it back from the position shown in Fig. 1, so as to disengage the sear 70 15, which will then rise under the influence of spring 14 to engage the hammer. The purpose of this feature of construction will be better understood when the operation is described.

75 The parts thus far described comprise the main features of my invention and while shown in the preferred form, the same may be modified in design and arrangement without departing from the scope of this invention.

80 Operation: To operate the firearm, the magazine 14 is loaded with a suitable number of cartridges and is inserted in place, as in Fig. 1. The operator then grasps the handle 9^a and pulls the breech-block back against the action of the closing spring 8. This compresses the hammer spring 14. When the breech-block 9 has retracted sufficiently far the sear 15 engages in notch 12^b 90 in the hammer, thus holding the latter retracted. The breech-block 9 is then permitted to advance under the action of the closing spring 8. This advance movement takes one cartridge from the magazine 4 and 95 forces it into the chamber of barrel 2. The firearm is then ready to fire. By pulling the trigger 17 the sear 15 releases hammer 12. The hammer 12 then springs ahead under the power of spring 14 and the firing-pin end 13 strikes the cartridge in the chamber of the barrel, exploding the same. The "blow-back" of the cartridge shell is imparted to the breech-block, which is forced back thereby and caused to repeat the operations previously described. During the rearward movement the discharged shell is extracted and ejected, and during the forward movement another loaded cartridge 100 from the magazine is introduced into the chamber of the barrel, ready for firing, as before. The hammer 12 has, as before, been caught by the sear 15 ready to be released at the proper time by pulling trigger 17. If the operator has held back the trigger and 105 has thereby caused the hammer-engaging end of the sear 15 to be depressed, the breech-block 9 will strike against the link 16 near the limit of its rearward excursion, 110 swinging it back, thus releasing sear 15, which thereupon springs up and engages the hammer so as to hold the same whether or not the trigger 17 is released, thus preventing premature firing. When the breech-block advances under these conditions, the 115 link 16 swings ahead (any suitable spring being provided to cause it to normally swing ahead) until the shoulder 16^a bears against the rear end of the projection 15^d. As soon 120 as the operator releases the trigger, the link 130

16 moves up, and the spring for operating the same swings it ahead until shoulder 16^a drops into the notch in the sear just above the projection 15^a, as shown in Fig. 1, so that by pulling the trigger the hammer may be again released.

In all probability, in practice, in many instances, it will be impossible for the user to release the trigger as quickly as the fire-arm would act to complete one cycle of operation, hence by having this safety trigger mechanism there is no danger of premature discharge of a second cartridge by reason of failure on the part of the trigger mechanism to engage and hold back the hammer at each cycle of operation of the parts.

What I claim is:

1. In an automatic repeating firearm, a breech-frame, a reciprocating breech-block, a hammer and firing-pin carried thereby, a sear carried by the frame and arranged to engage the hammer when retracted, a single spring coöperating with both the hammer and the sear, a trigger, and means for operatively connecting said trigger with said sear when said trigger is released and the breech-block is advanced from its rearmost position.
2. In an automatic repeating firearm, a breech frame, a reciprocating breech-block, a hammer and firing-pin carried thereby, a sear carried by the frame and arranged to engage the hammer when retracted, a sin-

gle spring coöperating with both the hammer and the sear, a trigger, and means for operatively connecting said trigger with said sear when said trigger is released and the breech-block is advanced from its rearmost position, said trigger being automatically disengaged from said sear by the breech-block when the latter is at its rearmost position.

3. In an automatic repeating firearm, a breech frame, a breech-block arranged to reciprocate therein, a cartridge holding magazine detachably carried by the breech frame and arranged underneath the forward end of the breech-block when the latter is advanced, a plunger like hammer carried by said breech-block, a spring mounted at one end in the frame and arranged to engage said hammer at its rear to press the latter forwardly, a closing spring arranged to the rear of the breech-block and operatively connected therewith and normally acting to advance the breech-block, a sear carried by the frame and arranged to retain the hammer in its rearmost position when in one position, a trigger, and means detachably connecting said trigger with said sear excepting when the breech-block is retracted to its rearmost position.
